CLAIM

The ornamental design for a mid-sole cleat as shown and described.

DESCRIPTION

FIG. 1 is a perspective view of a first embodiment of a mid-sole cleat showing our new design;

FIG. 2 is a top view thereof;

FIG. 3 is a side view thereof;

FIG. 4 is a bottom view thereof;

FIG. 5 is a front view thereof;

FIG. 6 is a back view thereof;

FIG. 7 is a perspective view of a second embodiment of a mid-sole cleat showing our new design;

FIG. 8 is a top view thereof;

FIG. 9 is a side view thereof;

FIG. 10 is a bottom view thereof;

FIG. 11 is a front view thereof; and,

FIG. 12 is a back view thereof.

(Continued)

The dashed lines show various portions and other elements in the figures for the purpose of illustrating unclaimed portions and form no part of the claimed design.

1 Claim, 6 Drawing Sheets
